UNITED STATES PATENT OFFICE.

CLARENCE J. SWINK, OF RED LION, OHIO.

EAVES-TROUGH.

SPECIFICATION forming part of Letters Patent No. 591,705, dated October 12, 1897.

Application filed June 15, 1897. Serial No. 640,799. (No model.)

To all whom it may concern:

Be it known that I, CLARENCE J. SWINK, of Red Lion, in the county of Warren and State of Ohio, have invented certain new and 5 useful Improvements in Eaves-Troughs; and I do hereby declare that the following is a full, clear, and exact description of the invention, which will enable others skilled in the art to which it appertains to make and use the same, 10 reference being had to the accompanying drawings, and to the letters of reference marked thereon, which form part of this specification.

This invention relates to certain new and 15 useful improvements in eaves-troughs, gutters, waste-pipes, &c.

The object of the invention is to provide 20 means for preventing corrosion in troughs, gutters, pipes, and the like where water is likely to collect and stand.

A further object of the invention is to construct a trough, pipe, or the like in such a manner that non-corrosible material may be easily placed where the water has the greatest tendency to settle.

A further object of the invention is to provide a non-corrosible trough, gutter, &c., simple, cheap, and durable in construction and effective in use.

30 The invention consists in certain novel features of construction and in combinations of parts, more fully described hereinafter, and particularly pointed out in the claims.

In the drawings, Figure 1 is a front elevation of a portion of a house showing my invention in use. Fig. 2 is a cross-section of the improved eaves-trough. Fig. 3 is a vertical longitudinal section of a waste-pipe, my improvement applied. Fig. 4 is a cross-section thereof. Fig. 5 is a top plan view of the trough.

Referring by letter to the drawings, *a* is a trough or gutter having the depressions *b* in its lowest point running longitudinally. In 45 this depression *b* is suitably secured a strip of non-corrosible material *c*, preferably zinc, the same length of each of the sections of gutter, but placed in such a way that it will overreach the section at one end, as at *e*, and leaving a recess at the other end for the next overlapping strip, as at *f*, so that the joints of the

gutter and of the non-corrosible material will not register, thereby assuring a tight joint that will not leak.

It is readily seen that the depression 55 strengthens the gutter, and when the zinc is secured therein a smooth surface is produced with no possibility of the water collecting anywhere but on said zinc or other non-corrosible material.

Where it is desired to apply my rust-proof device to waste-pipes, down-spouts, tubing, &c., the depression is made in the outer periphery of the pipe where it will rest against the house or other place where water will collect and cause corrosion. The non-corrosible material is then secured in the depression in the manner described, or, if desired, a strip of zinc or the like may be attached by means of solder to the outside of any pipe without 65 the depression. The depression is preferable 70 for durability, effectiveness, and appearances.

It is evident that various slight changes might be made in the forms, construction, and arrangement of the parts described without 75 departing from the spirit and scope of my invention. Hence I do not wish to limit myself to the exact construction herein set forth, but consider myself entitled to all such changes 80 that fall within the spirit and scope of my invention.

Having thus fully described my invention, what I claim as new, and wish to secure by Letters Patent of the United States, is—

1. An eaves-trough or gutter having a depression in its lowest portion and a strip of non-corrosible material secured in said depression substantially as described.

2. In an eaves-trough or gutter the combination of a depression in its bottom with a 90 strip of zinc or other non-corrosible material secured in said depression and arranged to lap over the joints of the sections of the trough as shown and described.

3. An eaves-trough or gutter comprising a 95 depression of the lowest point of the inner periphery thereof, a strip of non-corrosible material adapted to snugly fit in said depression and adapted to overlap the joints of the sections of the trough substantially as described.

4. The combination of an eaves-trough, tub-

ing &c. as described with the depression in its outer periphery, a strip of non-corrosible material secured in said depression and overlapping the sections of tubing, strengthening and forming tight joints of said tubing, substantially as described.

In testimony that I claim the foregoing as

my own I affix my signature in presence of two witnesses.

CLARENCE J. SWINK.
